PULL FOR DOORS, SLIDE PANELS, DRAWERS, DROP FRONTS AND THE LIKE

Carl B. Hinrichs, Charlotte, Mich., assignor to Structural
Products, Inc., Charlotte, Mich., a corporation of
Michigan

Filed Dec. 16, 1964, Ser. No. 83,055

Term of patent 14 years

(Cl. D10—8)

FIG. 1 is a perspective view showing a pull of my new design.

FIG. 2 is an enlarged end view of the pull of FIG. 1.

FIG. 3 is an partial front elevational view showing the left end of the pull of FIG. 1.

FIG. 4 is a partial rear elevational view of the pull of FIG. 1.

The dotted line showing of a drop front that is horizontally hinged to a rectangular cabinet is for illustrative purposes only.

I claim:

The ornamental pull for doors, slide panels, drawers, drop fronts and the like, substantially as shown and described.
